HENRY W. O'NEILL, OF ELMHURST, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed March 31, 1926. Serial No. 98 663.

This invention relates to telephone systems and particularly to a system for improving the efficiency of speech transmission.

It is an object of this invention to prevent loss in output energy of the transmitter of a telephone set ordinarily due to the receiver and conversely to prevent loss in the energy incoming to the receiver ordinarily due to the transmitter.

Another object is to control the output of sidetone in the receiver of a telephone set.

The invention has been embodied in an ordinary subscriber or telephone set comprising the usual induction coil and a transmitter and receiver element respectively included in the output and input circuits. A voice current responsive device is included in the output circuit with the transmitter so as to become actuated when the transmitter is used, while a second device is arranged to be controlled by the voice current responsive device to partly or wholly remove the receiver from the input circuit depending on whether or not a side-tone effect is desired. On the other hand, while the receiver is normally connected across the input circuit, the induction coil is not so connected but is arranged to be included in place of the receiver when the transmitter is actuated. Hence, the actuation of the transmitter may remove the receiver and connect the transmitter through the induction coil to the output circuit.

Telephone instruments or sets, whether employed at subscriber stations or at telephone switchboards, are, in general, connected by two conductors which serve for both outgoing transmission and for incoming transmission of a telephone conversation. This use of but two conductors usually obtains irrespective of whether a telephone set may be connected for service over circuits where the main line section may be formed of two conductors or may be formed of four conductors.

Heretofore, it has been the practice to connect both the transmitter and the receiver of a telephone set in fixed relation to the two conductors which serve as the exterior leads for a set. It therefore results that for outward transmission, a portion of the energy is absorbed in the circuits of the associated receiver and may not become effective over a line, while under incoming transmission, a portion of the energy is absorbed in the cir-

cuits of the transmitter and therefore may not be available for use in the telephone receiver.

In the use of telephone sets, an effect commonly referred to as side-tone is produced. This is principally due to the fixed interconnective relation of the transmitter and receiver as when the transmitter may be in use a portion of the speech energy is taken up by the receiver with the result that side-tone is produced. A further source of side-tone is from extraneous or room noises which may be picked up by a transmitter and rendered effective in the associated receiver of a set.

Side-tone may in general be divided into two classes which, for convenience here, may be referred to as detrimental and as beneficial side-tone, respectively. Detrimental side-tone adversely affects telephone transmission in three major ways. First, all side-tone from room or extraneous noises tends to decrease the intelligibility of incoming transmission. Second, if a person speaks loudly, the resulting greater volume of side-tone momentarily reduces the sensitiveness of the speaker's hearing, thereby rendering it more difficult to understand incoming transmission, and third, because of the unpleasant effect of an excess of side-tone a speaker is inclined to lower the voice, thus reducing the amount of outgoing transmission. On the other hand, beneficial side-tone may be described as a limited or predetermined amount of sound produced from outgoing speech only. Such side-tone may serve as a guide relative to the volume and the modulation of the voice and also may serve to indicate whether one may be speaking in proper proximity to the transmitter of a telephone set.

In telephone sets of the types where the receiver is connected in series with the output circuit of the associated transmitter, a maximum volume of side-tone will invariably be present. The greater portion of such side-tone is detrimental to transmission and in seeking to overcome this, telephone sets of types commonly referred to as anti-side-tone sets have been developed, particularly for use at telephone switchboards. The latter sets are usually based on a network arrangement which is formed of the output circuits of a transmitter with the circuits of a receiver, in such a manner that when the exterior leads

of the set may be connected to a line the impedance of which is equal to the impedance looking into the network, a minimum volume of side-tone only may be set up in the receiver.

- 5 Although arrangements of the latter sort may, to a certain extent improve the conditions as to excessive or detrimental side-tone, the idle transmission losses for both outgoing and incoming speech, as above pointed 10 out, are usually in excess of the losses had with the simple series arrangement already mentioned.

A further effect detrimental to telephone transmission is due to a phenomenon encountered in so-called 4-wire working, which is commonly referred to in the art as "echo" effect. In 4-wire systems, a line section proper is formed of two pairs of conductors, one pair for carrying transmission in one direction, as from east to west, while the other pair serves for transmission in the opposite direction, as from west to east. At each terminus, coil systems and balancing networks are usually provided so that a 4-wire line section 20 may merge into 2-wire circuits for service to respective telephone stations or sets. In circuits for commercial service, an appreciable amount of speech energy may become effective through the coil and balancing systems so that voice currents arriving over a pair from an eastern point may flow into and return to the originating point over the opposite or west to east transmission pair. A similar but inverse effect is present under 30 transmission in the opposite direction, from west to east. In case the length of a 4-wire line may be limited so that an inappreciable time is required for a circulating voice current to traverse the line section in returning to the originating station, the returning 40 energy may merely tend to augment the side-tone in the receiver at the latter point. In practice, however, the length of 4-wire circuits is usually such that an appreciable time intervenes between the instant of generation 45 of a voice current and its return and manifestation in the receiver of the originating instrument. This effect in the ear of a person speaking is that of an echo, and for this reason this phenomenon is commonly referred to as an echo effect. On long circuits this is 50 objectionable to the point of totally disabling a conversation. As a remedy for such effects, systems have been provided for use with 4-wire circuits, and are commonly referred to as echo-suppressor systems.

In addition to the operations of transmission and reception of speech, telephone sets when employed at telephone switchboards 60 are usually arranged for the carrying out of so-called "click" busy test operations.

One feature of this invention is the provision of a telephone set in which the receiver may not cause loss in the output circuits of its 65 associated transmitter, while, conversely, the

output circuits of a transmitter may not absorb or cause loss of incoming speech energy intended for the receiver.

Another feature is the provision of means whereby when desired, a limited and suitable 70 amount only of energy from a transmitter may be rendered effective with the associated receiver of a telephone set to provide beneficial side-tone, while effects arising from large volumes of voice energy or from extraneous or room noises which would result in detrimental side-tone may be substantially incapable of producing a detrimental amount of side-tone in the receiver of a set.

Another feature is the provision of a telephone set system for eliminating side-tone or echo effects peculiar to 4-wire line circuits and to permit so-called echo-suppressor arrangements, in general, to be dispensed with 80 in connection with circuits of the last mentioned type.

Another feature of the invention is the provision of a telephone set which in addition to affording the advantages set forth in the foregoing objects, may also be employed in 90 performing busy test operations.

In carrying out the present invention, a switching system capable of control by energy from voice currents is coordinated with the circuits of a telephone set in such a manner 95 that for incoming transmission, the receiver only may be connected while under outgoing transmission, the transmitter only may be connected to the exterior or service leads of a set. Therefore, under transmission in either 100 direction from a set, all of the speech currents may be available as useful energy for traversing a line and finally actuating the receiver at a distant station.

In situations where it may be desired to 105 provide beneficial side-tone, as above described, the switching system has been arranged in such a manner that a limited amount only of the speech energy from a transmitter may be directed into the associated 110 receiver, the path of such energy being adapted substantially to exclude current effects which would otherwise set up detrimental side-tone effects.

The coordination of the circuits of a telephone set of the present system automatically to render but one of the transmission devices, as the transmitter or the receiver respectively, effective at one time with the leads serving a set, results in nullifying energy 115 heretofore effective in setting up detrimental side-tone or echo effects peculiar to 4-wire line circuit arrangements.

In providing a telephone set to combine the several advantages of elimination of 120 wasteful loss of speech, elimination of detrimental side-tone effects, nullifying of echo effects with provision for applying busy test operations, the devices of the present invention have been coordinated in such a man- 125

ner that certain portions of the busy test devices may also serve for eliminating detrimental side-tone while providing beneficial side-tone.

5 This invention is illustrated in the accompanying drawing in which

Fig. 1 shows a telephone set provided with a relay system controllable by energy from voice currents for automatically switching the 10 circuits of the set to prevent wasteful loss of speech energy, for eliminating detrimental side-tone while affording beneficial side-tone effects and for rendering echo effects ineffective.

15 Fig. 2 shows a telephone set which differs from the set of Fig. 1 principally in that all side-tone effects are eliminated, while details of the relay system also differ from the system of the first figure.

20 Fig. 3 shows a set arrangement which differs from that of Fig. 1 principally in that the relay system has been simplified.

25 Fig. 4 shows a set which differs from that of Fig. 1 principally in that a vacuum tube is employed in the relay system, while in

Fig. 5 a set is shown which in addition to providing the service features of the set shown in Fig. 1 also provides for the carrying out of busy test indications.

30 Other objects and features of the present invention will be apparent from the following description and the appended claims:

35 Throughout the various views of the drawing like characters of reference have been employed for indicating like or similar parts.

40 In a more detailed description of this system, conductors 1 and 2 serve a receiver 3 and transmitter 4 of a telephone set (Fig. 1). In the normal position of the circuits which is the position shown in the drawing, it may be noted that the lower contacts of a normally energized relay 5 serve to establish the receiver 3 directly to the conductors 1 and 2. A retardation coil 6 is shunted during such 45 periods due to this closed condition of the contacts of the relay 5, while the secondary winding of an induction coil 7 is retained open at the upper contacts of this relay 5. Therefore, voice currents which may arrive 50 over the leads 1 and 2 may complete circuit through the receiver 3 only, as all other paths from these conductors are disconnected.

55 For outward transmission, current from a battery 10 may energize a local circuit formed of a retardation coil 11, the transmitter 4 and the primary winding of the induction coil 7. The reactance of the coil 11 substantially prevents changes of current effect to the battery as may be set up by 60 voice effects in the transmitter 4. Therefore, a condenser 12 is connected in bridge on the series formed of the transmitter 4 and the primary winding of the induction coil 7 for the purpose of permitting the necessary 65 voice frequency changes to be established in

the induction coil. Connected in parallel with the condenser 12 is a series formed of a condenser 13 and a sensitive alternating current relay 14. This relay may preferably be

70 of the acceleration type shown in my co-pending application—Serial No. 526,152, filed Dec. 31, 1921.

Normally the contacts of the relay 14 are closed in completing an obvious circuit from grounded battery to retain the relay 5 energized. When the 75 transmitter 4 may be in use, however, the high speed relay 14 responds to the alternating currents corresponding with changes in potential level on the condenser 12, and maintains its contacts separated in disconnecting the relay 5. Therefore, so long as voice effects may be present from the transmitter 4, the relay 5 will stand released thereby removing the shunt from around the impedance coil 6 in series with the receiver 3 as

80 connected to the leads 1 and 2, while closure of the upper contacts of the relay 5 will connect the secondary winding of the induction coil 7 to the conductors 1 and 2. In

85 the latter position of the circuits, the transmitter 4 is rendered effective for transmission over the pair formed of conductors 1 and 2, while a series path formed of the receiver 3 and the impedance 6 is connected

90 to bridge on this pair. Due to the presence of the retardation coil 6 in series with the receiver, any tendency to excessive or detrimental side-tone is prevented, although a

95 predetermined amount of side-tone in the form of energy from the transmitter 4 may become effective in the receiver 3 and serve 100 as beneficial side-tone. The presence of the retardation coil in series with the receiver results in a minimum amount of energy in this path. Therefore, a maximum amount 105 of the energy which may be set up through the transmitter 4 may be effective for transmission over the conductors 1 and 2 to the receiver at a distant station, (not shown).

110 Suitable proportioning of the capacity 13 in relation to the inductance of the relay 14 should be provided to prevent a condition of series resonance for the relay 14 either through the condenser 12 or through the primary winding of the induction coil 7 and

115 the transmitter 4, at frequencies other than voice range.

120 In addition to supplying beneficial side-tone from the transmitter 4, the presence of the receiver 3 on the exterior conductors 1 and 2 during outward transmission from the telephone set under description, also serves for reception of any indication from a distant station at which the other party to a

125 conversation may speak in seeking to interrupt a speaker when such action may be desired. On reception of such an indication the first party may cease speaking, whereupon the relays 14 and 5 will restore to disconnect the output circuit of the transmitter 4 and

130

connect the receiver alone for reception of all energy which may arrive from over the conductors 1 and 2.

In the arrangement of Fig. 2 a resistance 6 is interposed in the current supply path for the relay 5, while the contacts of the relay 14 are connected to normally shunt down the relay 5. Therefore, the latter relay is normally de-energized, and in order 10 to correct for such inverse position of this relay with regard to the corresponding relay of Fig. 1 the leads to the contacts of this relay have been transposed. Omission of the reactance 6 in the arrangement of Fig. 2 is 15 to dispense with all side tone effects. In the normal position of the circuits the relay 5 will stand in the position in which it is shown in the drawing, thereby establishing the receiver 3 to receive all energy which 20 may arrive from over the leads 1 and 2.

In this arrangement the circuit of the relay 14 is connected in parallel to the secondary winding of the induction coil 7. Therefore, under speech energy at the associated transmitter 4 relays 14 and 5 will respond to effect entire disconnection of the receiver 3 and connection of the output circuit of the transmitter system to the conductors 1 and 2. Therefore, all of the speech 25 energy created in the transmitter may become effective over any form of line circuit which may be connected to the leads 1 and 2.

In the arrangement of Fig. 3 the secondary winding of the induction coil is permanently 30 connected to the conductors 1 and 2, while the receiver 3 is also connected to the latter conductors in such a manner that a resistance or impedance 6 is normally shunted by the closed contacts of the relay 14. Therefore, 35 for incoming currents from over the conductors 1 and 2 the receiver 3 will be connected in parallel with the output circuit of the induction coil 7. In this arrangement the circuit of the relay 14 is connected in bridge 40 around the transmitter 4. Under operation of the transmitter the response of the relay 14 removes the secondary winding of induction coil 7 and interposes the resistance 6 in series with the receiver 3. This placed the 45 receiver in condition to afford beneficial side tone as already described for the telephone set of Fig. 1. Under reception of incoming transmission, the secondary winding of the induction coil may absorb some of the arriving 50 energy. Therefore, the use of this arrangement may be limited to situations where this loss of energy may not seriously affect the transmission.

In the arrangement of Fig. 4 a three element vacuum tube amplifier rectifier 18 has 60 been substituted for the acceleration or vibratory type relay 14 of the other arrangements. In the drawing, the elements of the tube have been shown in conventional form. 65 A grounded "A" battery A supplies current

for the filament or cathode element. The grounded source 10 serves in supplying "C" battery potential by way of the retardation coil 11 and a resistance 19 to the grid or control element, while a grounded "B" battery B supplies current by way of the winding of the relay 5 to the plate or anode element of the tube. Normally the negative potential of the C battery establishes a condition of "bias" in the tube to limit the current through the relay 5 so that this relay may be inert as shown in the drawing. Under this condition, the resistance 6 will be shunted, and the receiver 3 will be connected to the service leads 1 and 2, while the output circuit of the induction coil will be disconnected. Under voice effects from the transmitter 4, the resulting potential changes at the condenser 12 will overcome the negative bias of the tube 18 to permit sufficient current in the plate circuit to effect response of the relay 5. This switches the leads 1 and 2 to the output circuit of the transmitter 4, while the resistance 6 will be established in series with the receiver 3 which will thus be a bridge across the conductors 1 and 2. The service effects with this arrangement substantially correspond with those already described for the arrangement of Fig. 1.

In the arrangement of Fig. 5 the leads 1 and 2 may be considered as extending to an order wire or call circuit terminating at a distant exchange point, while the leads 21 and 22 may be considered as joined to line conductors which form a trunk circuit terminating at the same distance exchange (not shown). A plug 23 serves for terminating this trunk or toll line circuit at an exchange in association with the system of Fig. 5. This trunk circuit may be considered as one of a group of trunk circuits which may terminate at a switchboard position served by the telephone set now under description.

Let it now be assumed that a distant operator transmits a request by way of the call circuit, conductors 1 and 2, for a certain connection. The receiver 3 stands normally connected by way of the upper contacts of the relay 5 to these conductors for reception of such requests. Assuming now that the operator assigns the trunk circuit ending in plug 23 for such a connection, this information will be given to the distant originating operator over the same call circuit. For this, speech at the transmitter 4 effects response of the relay 14 the circuit of which is in parallel with the primary winding of the induction coil 7 in this arrangement. This removes the shunt to permit response of the relay 5, thereby switching the leads 1 and 2 to the output winding the induction coil 7, and also inserts the left hand winding of a transformer 25 in series with the receiver 3 as now joined to the conductors 1 and 2. This winding of the transformer 25 now

serves as an impedance similar to the unit 6 of the other arrangements, for restricting the amount of the outgoing energy which may become effective through the receiver 5 as desirable or beneficial side-tone.

In proceeding to establish the desired connection the inward or switching operator first touches the tip (uppermost) member of the plug 23 to the shell member of a jack (not shown) of the desired line, thus making a busy test operation to determine whether the line is idle. Assuming now that the line may be busy, potential from grounded battery will be present on the shell of the assumed 10 jack and current may flow over the uppermost member of the plug 23, the normal or upper contacts of a relay 26, thence to ground through the right-hand or primary winding of the busy test transformer or repeating 15 coil 25. This establishes an impulse of induced current in the left-hand or output winding of the repeating coil. This impulse may traverse a closed loop which includes the telephone receiver 3 and the secondary winding 20 of the induction coil 7. The resulting "click" in the telephone receiver indicates that the desired line is busy. Due to the character of the sound produced by such busy 25 test operations they are commonly referred to as click busy tests.

In the event that the desired line may have been idle, absence of battery potential at the assumed jack would have resulted in no sound when the test was made. Therefore, 30 in establishing the connection, the plug 23 may be assumed to have been inserted into the jack (not shown). Current from grounded battery through the winding of a relay 26 would then flow over the lowermost 35 or "sleeve" strand of the connection, the jack portion of which is well understood in the art and therefore has not been shown in the drawing. Response of the relay 26 switches the upper strand of the cord circuit 40 from the busy test coil 25 to the conductor 21 of the trunk circuit. In this manner, the circuit of the trunk is isolated from the telephone set and the circuit is completed 45 for use on the connection established.

50 It will now be clear that the transformer 25 has a dual use, as it serves at one time as a busy test coil and at another time as a retardation coil, relative to preventing detrimental side-tone while permitting beneficial 55 side-tone to become effective through the receiver 3.

The telephone set of Fig. 3 may also be employed at switchboard positions where ordinary cord circuits may be present. For 60 this, a second plug in duplicate of the plug 23 may be joined to the conductors 21 and 22. These conductors will then form the

two main strands of the cord circuit. A so-called talking key (not shown) may then be considered as present for joining the conductors 1 and 2 of the operator's set to the conductors 21 and 22 of the cord circuit. From the description already given it will be obvious how such a key may render the telephone set effective for performing busy 65 test operations and for talking over connections which may be established from the cord circuit.

It may be pointed out that by dispensing 70 with the impedance unit 6 or its equivalent, the arrangements of either Figs. 1, 3, 4 or 5 may then correspond with the arrangement of Fig. 2 relative to entire elimination of the telephone receiver 3 during periods the associated transmitter 4 of a set may be in 75 use.

The relay 5 preferably should be of a type 80 to respond quickly in connecting the circuits of the associated transmitter but somewhat slow to respond in the direction of disconnecting the output circuit of the transmitter from the exterior leads. This is more particularly to prevent switching effects between syllables or words. The delay or 85 "lag" effect, however, to be such that switching may take place immediately following definite cessation of speech at an associated transmitter. The delay characteristics have been indicated by conventional markings in 90 the drawing.

95 What is claimed is:

1. In a telephone set circuit, a transmitter system including a transmitter, a source of current and an induction coil having a primary and a secondary circuit, a receiver, a 100 service lead connected to said receiver, and switching means responsive to voice currents in the primary circuit of said induction coil for transferring said lead from the receiver to the secondary circuit of said induction 105 coil.

2. In a telephone set including a transmitter, a source of current, a receiver, an induction coil, a retardation coil and a transmitter, a primary circuit including 110 said source, retardation coil, transmitter and one winding of said induction coil, a condenser connected in bridge of the series formed of said transmitter and said winding of the induction coil, a service lead normally connected to said receiver, and relay means connected in parallel with said condenser and responsive to current impulses generated by said transmitter for transferring said lead from said receiver to the other 115 winding of said induction coil.

120 In witness whereof, I hereunto subscribe my name this 30th day of March A. D., 1926.

HENRY W. O'NEILL.
